DESIGN FOR A TEXTILE FABRIC

Benjamin W. Rosenblum, New York, N. Y.

Application February 28, 1941, Serial No. 99,269

Term of patent 3½ years

To all whom it may concern:

Be it known that I, Benjamin W. Rosenblum, a citizen of the United States of America, residing in New York city, county of New York, and State of New York, have invented a new, original, and ornamental Design for a Textile Fabric, of which the following is a specification, reference being had to the accompanying drawing, forming part thereof, wherein the figure of the drawing is a plan view of a textile fabric showing my new design.

I claim:

The ornamental design for a textile fabric, substantially as shown.

BENJAMIN W. ROSENBLUM.
